DESIGN FOR A SCARF

Joseph J. Vellanti, New York, N. Y.

Application November 10, 1947, Serial No. 142,419

Term of patent 3½ years

(Cl. D3—12)

To all whom it may concern:

Be it known that I, Joseph J. Vellanti, a citizen of the United States, residing at New York, in the county of New York and State of New York, have invented a new, original, and ornamental Design for a Scarf, of which the following is a specification, reference being had to the accompanying drawing, forming a part thereof.

In the drawing the figure is a top plan view of a scarf, showing my new design.

I claim:

The ornamental design for a scarf, as shown.

JOSEPH J. VELLANTI.
